TOP FOR STOCKINGS

Max Nebel, Chemnitz, Germany; vested in the
Allen Property CustodianApplication August 12, 1938, Serial No. 224,547
In Germany December 4, 1937

1 Claim. (Cl. 66—172)

This invention relates to single-layered fabric stocking tops.

An object of this invention is to provide a stocking top which is prevented from ravelling of the initial course.

Another object of this invention is to provide a stocking top which will not only be held against ravelling, but will also be held against rolling.

A further object of this invention is to provide a stocking top having an elastic weft thread laid therein in such a manner as to hold the top against ravelling and also against rolling.

A further object of this invention is to provide a stocking top in which a weft thread is laid through the sinker loops of the initial course, and succeeding, alternate sinker loops are also provided with an elastic weft thread.

A further object of this invention is to provide a stocking top which may be formed with patterns and wherein certain of the weft threads are extended through the loops forming the patterns.

In the drawings:

Figure 1 shows a fragmentary stocking top having an elastic weft thread laid therein according to an embodiment of this invention.

Figure 2 shows a fragmentary stocking top of the pattern type having a weft thread laid therein.

Figure 3 shows a fragmentary stocking top embodying another form of this invention.

Figure 4 shows a fragmentary stocking top embodying a further form of this invention.

Figure 5 shows substantially a full stocking top embodying a further form of this invention.

Figure 6 shows substantially a full stocking top embodying a further form of this invention.

Figure 7 shows a fragmentary stocking top embodying a further form of this invention.

Figure 8 shows in fragmentary form a full-length stocking having a top thereon formed according to an embodiment of this invention.

Figure 9 shows in fragmentary form a three-quarter length stocking having a top thereon formed according to an embodiment of this invention.

Figures 10 to 13 show the successive steps necessary to lay three weft threads in a portion of the top.

Figures 14 to 16 show the successive steps necessary to lay a single weft thread in a portion of the top embodying a pattern.

Referring to the drawings, and first to Fig. 1, the non-elastic thread forming the stocking top proper is formed in successive courses *a*, *b*, *c*, etc., on needles *3a*, *3b*, *3c*, etc., and presser needles 4.

Each course includes sinker loops 2 and opposes needle loops 3, with the needle loops 3 of a preceding course interlocked in the sinker loops of a succeeding course.

5 In each form of this invention the weft strand or thread, which is of elastic characteristic, is designated by the numeral 1, and the several courses of the fabric are designated *a*, *b*, *c*, etc.

As shown in Fig. 1, the weft strand 1 is disposed under the adjacent arms of two sinker loops 2, and is then disposed over the adjacent arms of succeeding pairs of sinker loops 2. In the initial course of the stocking top there are preferably two or more weft strands, which in

10 Fig. 1 are designated *1a*, and *1b*. The strand *1b* is integral with the strand *1a*, but is laid oppositely from the strand *1a*, that is where the strand *1a* engages beneath a pair of sinker loop arms the strand *1b* engages over the same sinker loop arms, and where the strand *1a* engages over a pair of sinker loop arms the strand *1b* engages beneath the same sinker loop arms.

The second course *b* is preferably skipped in the laying of the weft strand 1, but in the third course *c* the weft strand 1 is laid in the same manner as the strand *1a*.

In Fig. 2 there is disclosed a fragmentary portion of an open mesh top showing only two courses *a* and *b*. In this form of top, the strand 1 is laid in the same manner as the initial strands *1a* and *1b* in Fig. 1, the two weft strands in Fig. 2 being designated *1a* and *1b*, and the mesh loops 8.

In Figure 3 the initial course has three elastic weft strands laid therein, the strands being designated *1a*, *1b*, and *1c*. The first strand *1a* is laid over a pair of adjacent arms of a pair of adjacent sinker loops 2, and is then laid under four adjacent arms of two succeeding sinker loops 2.

The second strand *1b* is laid similar to the first strand *1a* but in reversed manner, the strand *1b* being laid over the first succeeding adjacent pair of arms of the sinker loops following the overlay of strand *1a*. The third strand is laid in a manner similar to strand *1b*, but the overlay of strand *1c* engages a pair of sinker loop arms succeeding the pair of sinker loop arms on which the strand *1b* overlies. In course *a* the needle loops 3 are not provided with a weft strand, but in course *b* the needle loops thereof which are interlocked with the sinker loops of course *c* have two weft strands *1a* and *1b* laid therethrough which are laid similar to strands *1a* and *1b* in the initial course.

40 The needle loops in course *d* which are interlocked with the sinker loops in course *e* have 45

45

50

55

55

only 1 weft laid therethrough which is laid similar to the initial strand $1a$ in course a .

In Figure 4 a fragmentary pattern type stocking top is disclosed having a pair of weft strands $1a$ and $1b$ laid in the initial course a thereof, and a single strand is laid in the interlocked strands between courses b and c . In Figure 4 the weft strand $1a$ is laid over two sinker loop arms and then under two sinker loop arms, and the strand $1b$ is laid oppositely from strand $1a$. In the alternate course c a single weft strand is laid under the strands 6 , over mesh strands 1 and 8 of one pattern section, and then the strand in course c is reversed.

In Figure 5 there are four weft strands in the initial course a the first strand $1a$ being laid over six sinker loop arms and then under a pair of sinker loop arms, and the strands $1b$, $1c$, and $1d$ are laid in a similar manner but with the underlay staggered from the preceding weft strand. In this form a single weft strand is also laid through the needle loops of course a and through the sinker loops of course b , this single succeeding weft strand being laid similar to the initial strand $1a$ of this form. Additional single weft strands may also be laid in courses d , h and k .

In Figure 6 there is disclosed a pair of weft strands $1a$ and $1b$ in the initial course a , and single strands in courses b , c , e , f , m , and o . The weft strands in Fig. 6 are laid similar to the weft strands in Fig. 4, that is, they are laid over a pair of sinker loop arms and then under a pair of sinker loop arms, with the strand $1b$ engaging over the pair of arms which are under-lain by the strand $1a$.

In Figure 7 there is disclosed a top having three

weft strands $1a$, $1b$, and $1c$, in the initial course a thereof, three weft strands in course b thereof, two weft strands in each of courses c and d , and a single weft strand in course e . The weft strands in Fig. 7 are laid similar to the strands in Fig. 2.

Figures 10 to 13 show diagrammatically the manner in which the weft strands $1a$, $1b$ and $1c$ are laid. The strand $1a$ is disposed beneath needle $3b$, over needle $3a$, and from needle $3b$ is extended over needles $3c$ and $3d$. Strand $1b$ is started under needle $3a$ and then over needles $3b$ and $3c$. Strand $1c$ is started over needles $3a$ and $3b$ and then under needle $3c$.

13 In Figures 14 to 16 there is disclosed the manner of laying the weft strand in a tuck pattern. As disclosed in Fig. 15 the weft strand is disposed over and under succeeding needles so as to position the strand 1 in the manner shown in Fig. 16.

20 What is claimed is:

In a stocking top formed of a single layer of mesh fabric having sinker loops and needle loops, elastic weft threads worked into the mesh of the fabric, said weft threads being disposed in spaced apart weft lengths worked into alternate courses of interlocked sinker and needle loops, the initial course of sinker loops having work therethrough at least a pair of weft threads disposed in crossed relation with respect to the opposite arms of certain of said initial sinker loops, succeeding weft threads being worked over one arm and under the opposite arms of sinker loops of alternate succeeding courses and disposed on only one face of adjacent needle loops interlocked with said latter sinker loops.

MAX NEBEL.
